UNITED STATES PATENT OFFICE.

FREDERICK DIETZ, OF NEW YORK, N. Y., ASSIGNOR TO R. E. DIETZ COMPANY, OF NEW YORK, N. Y.

LAMP-SOCKET.

1,073,477.

Specification of Letters Patent. Patented Sept. 16, 1913.

Application filed February 1, 1911. Serial No. 606,013.

To all whom it may concern:

Be it known that I, FREDERICK DIETZ, a citizen of the United States, residing at New York, in the county of New York and State of New York, have invented a new and useful Improvement in Lamp-Sockets, of which the following is a specification.

This invention relates to that class of sockets which are applied to lamps, lanterns and other articles for attaching the same to a supporting prop, holder or standard. These props or holders are sometimes round in cross section and sometimes rectangular, oblong or flat and connection is impossible when the lamp or lantern has a flat socket while the prop is round, or vice versa.

The object of this invention is to provide a simple, convenient and cheap socket which is suitable for connection with either form of prop.

In the accompanying drawings: Figure 1 is a front elevation, Fig. 2 a vertical section on line 2—2, Fig. 1, Fig. 3 a rear elevation, and Fig. 4 a top plan view of this improved socket. Fig. 5 is a perspective view of the same attached to a round prop. Fig. 6 is a top plan view of a modified form of the socket. Fig. 7 is a perspective view of a flat prop.

Like reference characters refer to like parts in the several figures.

Referring to Figs. 1—5 and 7, the body of the socket comprises a round front portion A of the proper shape to fit upon a round prop B, and a flat or rectangular rear portion C of the proper shape to fit upon a flat or rectangular prop D. The round prop B rises from a horizontal arm b which is provided with an attaching clamp b', and the flat prop D rises from a horizontal arm d provided with an attaching flange d'.

The round front portion A and the flat rear portion C of the socket are formed integrally, preferably of sheet metal, and the cavities of the two portions communicate, so that the round front portion is partially open at the rear, in a circumferential direction, the junction points e between the front portion and the rear portion being on opposite sides of an upright slot or opening by which the cavities communicate. The curvature of the front portion is sufficiently greater than a half circle to cause this portion to seat itself firmly upon a round prop. The rear wall of the flat portion C is

composed of two upright parts f f which extend inwardly from the side edges of the rear portion but are not joined together, being separated by an open space g. Each part f of the rear wall is provided at its upper and lower ends with a lip h which is inserted in a slit in the plate or wall H of the lamp, lantern or other article to which the socket is secured and which is bent over or clenched on the opposite side, as represented in Fig. 2. These lips are represented by dotted lines in Fig. 3 in the flat or unbent position.

The socket preferably tapers upwardly in order to enable the same to seat itself firmly upon the prop which is similarly tapered.

When the socket is made of sheet metal or other flexible material, the round portion as well as the flat portion is capable of springing or yielding somewhat in applying the socket to the prop, whereby a close fit may be secured and rattling be prevented, even if the socket and prop are not exactly of the same size or form.

The round portion is preferably provided in its lower edge with an approximately semi-circular recess i which permits the socket to extend down on both sides of the horizontal arm b of the round prop, as represented in Fig. 5, so that the round portion straddles this arm, whereby the socket is prevented from turning on the prop. This security against turning may be still further increased by providing the prop near its junction with the horizontal arm with an upright rib or lug k and the socket with a corresponding elongated recess l which extends upwardly from the recess i and into which this rib engages.

In the modified construction of the socket represented in Fig. 6, the front portion M is half round and the flat rear portion N is so shaped that the round prop, indicated by a dotted line, is confined in the half round portion by the plate or wall O of the lamp or lantern to which the socket is secured and which forms the rear wall of the socket. In this construction the side pieces p of the socket are turned outwardly and are secured to the wall O by rivets or other suitable means.

I claim as my invention:

1. A flexible attaching socket for lamps, lanterns and other articles comprising a rounded front portion and a flat rear por-

- tion which have communicating cavities, the rounded front portion adapted to fit a round prop and the flat rear portion adapted to fit a flat prop, said socket having flat front 5 walls which extend outwardly from the rear edges of the rounded front portion, side walls which extend rearwardly from the outer ends of said flat front walls, and separated attaching flanges which extend 10 from the rear ends of said side walls parallel with said flat front walls, substantially as set forth.
2. An attaching socket for lamps, lanterns and other articles comprising a rounded 15 portion and a flat portion which have communicating cavities and having its rear wall composed of separated plates which extend from the side edges of the flat portion inwardly, substantially as set forth.
20. 3. An attaching socket for lamps, lanterns and other articles comprising a rounded portion and a flat portion which have communicating cavities and having its rear wall composed of separated plates which extend 25 from the side edges of the flat portion inwardly, said plates being provided at their

upper and lower ends with attaching lips, substantially as set forth.

4. The combination with a prop having a horizontal attaching arm at its lower 30 end, of an attaching socket comprising a rounded front portion and a flat rear portion, said rounded portion being provided at its lower end with side portions which extend downwardly on opposite sides of the 35 attaching arm, substantially as set forth.

5. The combination with a prop having at its lower end a horizontal attaching arm and a lug near its base above said arm, of an attaching socket provided at its lower 40 end with side portions which extend downwardly on opposite sides of the attaching arm and between said side portions with a recess which extends upwardly into said rounded portion and into which said lug 45 engages, substantially as set forth.

Witness my hand in the presence of two subscribing witnesses.

FREDERICK DIETZ.
